UNITED STATES PATENT OFFICE.

EDGAR H. FREEMAN, OF TRENTON, NEW JERSEY, ASSIGNOR TO CIRCLE F MFG. CO., OF TRENTON, NEW JERSEY, A CORPORATION OF NEW JERSEY.

ELECTRIC SOCKET.

Application filed July 10, 1926. Serial No. 121,668.

This invention relates to electrical sockets, and more particularly to a socket of the all porcelain type adapted for use in connection with a metal cap.

- 5 In many installations porcelain sockets can be used to advantage in place of sockets of the brass shell type, but the difficulty heretofore encountered in connection with their general use has been the lack of suitable and approved means for connecting the porcelain body with a metal cap, especially where the cap is more or less concealed or inaccessible. Porcelain sockets are generally cheaper than brass shell sockets and 15 where sockets of the latter type are hidden by a husk or ornamental casing or covering, it is quite apparent that the cheaper porcelain socket may be substituted and thus lower the cost of the installation. Also underwriters' requirements specify the use of porcelain sockets in places where brass shell sockets cannot be used but there is no objection to using porcelain sockets with metal caps. Therefore, it is also advantageous 20 from a manufacturing standpoint to provide a porcelain socket constructed in such a way that it may be used with a standard metal cap of the type used on the metal shell sockets, since a standardized porcelain socket 25 may be made to be interchangeably used with a standard metal cap. This feature is also advantageous from the standpoint of permitting dealers to stock a porcelain socket body for use in connection with standard metal caps without the necessity of carrying 30 separate caps for both kinds of sockets.

Accordingly, the present invention has primarily in view a novel construction which contemplates an all porcelain socket having 35 special features which permit of its being readily inserted in a metal cap in such a way that it will be readily and positively locked against movement in the direction of the longitudinal axis of the socket as well as 40 against rotational movement by the mere act of telescoping one end of the porcelain body into the cap. On the other hand the invention contemplates a construction whereby the porcelain body may be readily unlocked 45 or disengaged from the cap with the aid of a screw driver or equivalent tool which may be inserted in a small place to release the locking means.

With the above and other objects in view

which will more readily appear as the nature 55 of the invention is better understood, the same consists in the novel construction, combination and arrangement of parts herein-after more fully described, illustrated and claimed.

60 A preferred and practical embodiment of the invention is shown in the accompanying drawings in which:—

Figure 1 is an elevation of the invention, the same illustrating the porcelain socket 65 and metal cap separated and about to interlock.

Figure 2 is a side elevation, partly in section of the interlocked porcelain socket and metal shell.

70 Figure 3 is a top plan view of the porcelain socket.

Figure 4 is a bottom plan view of a metal cap.

Figure 5 is an enlarged detail view of the 75 yielding locking means for holding the cap and socket together.

Figure 6 is an enlarged detail view illustrating the manner in which the metal cap seats on the porcelain body.

80 Similar reference characters designate corresponding parts throughout the several figures of the drawings.

According to the embodiment of the invention shown in the accompanying drawing 85 it will be observed that the porcelain socket is designated generally as S and preferably includes a porcelain casing or shell A and a wiring base B adapted to telescopically fit within and engage with a metal cap C. As 90 previously indicated, the metal cap C is intended to be of a standard type adapted for use in connection with a brass shell line of sockets and is provided as usual with the attaching nipple 1 and the annular flange or 95 shell receiving skirt portion 2. This skirt portion is provided with a plurality of inwardly pressed keeper lugs 3, which as shown in Fig. 5 provide inwardly offset locking shoulders 4 throughout the interior surface of the flange or skirt. Also as will be 100 observed from Fig. 4 the intervening spaces between the keeper lugs 3 provide a plurality of grooves 5, which as will presently appear assist in preventing relative rotational movement between the cap and the socket.

105 The wiring base B of the socket assembly is provided with special features of construc-

tion which permit of the socket having a universal locking engagement with the standard cap structure described so that a mere insertion of the wiring base portion 5 of the socket into the cap will affect the desired interlock. As will be observed from the drawings these special features include the formation of a plurality of spaced ribs 6 on the base above the attaching flange portion 7 thereof which meets the shell or casing A and resilient locking tongues 8 which are provided with the struck-out catch projections 9 which provide locking shoulders 10 adapted to engage with the locking shoulders 4 of the cap when the socket and cap are interlocked.

The locking tongues 8 are housed within recesses 11 which extend from the top of the wiring base downwardly through the porcelain flange 7, and as will be observed from the drawings the said tongues are secured to the wiring base by means of the fastenings 12. As shown, the locking tongues are of substantially angular formation so that the body portion thereof having the struck-out catch projections 10 thereon is off-set from the bottoms of the recesses to permit of the ready depression of the tongues to effect the disengagement of the catch projections from the keeper projections on the cap when it is desired to detach the cap and socket. To assist in the facile detachment of the cap and socket the locking tongues are provided with the offset manipulating flange portions 13, which as shown in Fig. 5 project beyond the surface of the cap a sufficient distance to be easily engaged by a screw driver or other tool which may be inserted parallel to the face of the shell or casing A. And, to prevent the chipping of the flange 7 by the metal cap it will be observed from Fig. 6 that the ribs 6 are of sufficient height to engage with the shoulder 2^a of the cap so that the lower edge 2^b of the flange will not strike the porcelain flange 7.

The wiring base B is also provided with the central wire receiving opening 14 which permits the passage of the wires down to the binding terminals (not shown) carried by the wiring base and secured to the bottom face thereof by the fastenings 15 shown in Fig. 3.

From the foregoing it will be apparent that the wiring base B includes the porcelain ribs 6 which fit within the grooves 5 of the cap to prevent relative rotation between the socket and the cap when the same are interlocked, while at the same time the locking tongues 8 provide means for locking the cap and socket against longitudinal separation.

In practice the cap C may be installed on the fixture fitting in the usual manner and the wires drawn through the same and then passed through the opening 14 in the wiring

base to be connected to the line wire terminals thereof. It will of course be understood that the casing portion A of the socket and the wiring base are separated to permit of this attachment of the line wires, after which the wiring base and casing portion of the socket are secured together so that by merely grasping the casing A at its lower or open end and moving the entire socket toward the cap, the desired interlock will be effected immediately upon the wiring base fully entering the cap. Due to the universal character of the novel means provided on the wiring base, it will be apparent that the entire socket may interfit with the cap in any circumferential position, and when the cut edges 10 of the catch projections 9 engage with the cut metal shoulders 4 of the keeper lugs 3, it will be impossible to separate the socket and cap without depressing the locking tongue in the manner heretofore indicated. In that connection it may be pointed out that although two locking tongues are provided, it is only necessary to depress one of the tongues in order to accomplish disengagement.

It will be apparent that a distinctive feature of the invention is the provision of porcelain as well as resilient metal locking means on the wiring base for engaging with a standard cap to obtain the features heretofore pointed out.

Without further description it is thought that the features and advantages of the invention will be readily apparent to those skilled in the art and it will, of course, be understood that changes in the form, proportion and minor details of the construction may be resorted to without departing from the spirit of the invention or the scope of the appended claims.

I claim:

1. An electrical socket including in combination, an interchangeable metal cap and a porcelain body, said body having an integral offset portion, and a resilient metal locking tongue fastened thereto, said integral offset portion and metal locking tongue adapted to detachably interlock with the cap.

2. An electrical socket including in combination, a standard metal cap having a plurality of keeper lugs thereon, and a porcelain body having integral offset portions adapted to engage between said keeper lugs and resilient metal locking tongues fastened to said body and having means for detachably engaging said keeper lugs.

3. An electrical socket including in combination, a standard metal cap having a plurality of spaced keeper lugs thereon presenting locking shoulders and intervening grooves, and a porcelain body having spaced ribs for entering said grooves and resilient metal tongues fitted to the body and having offset catch projections for engaging with the locking shoulders of said keeper lugs.

4. A construction for electrical sockets wherein porcelain bodies are interchangeable with standard all-metal caps comprising in combination, an all-metal cap having a plurality of spaced keeper lugs thereon presenting horizontal locking shoulders and intervening grooves parallel with the axis of the cap, spaced ribs formed on the porcelain body for entering said grooves, and resilient keeper elements fitted to the body and adapted to engage with said locking shoulders.
5. In testimony whereof I hereunto affix my signature.

EDGAR H. FREEMAN.
